CLAIM

I claim the ornamental design for a walking aid attachment, as shown and described.

DESCRIPTION

FIG. 1 is a top perspective view of the walking aid attachment

FIG. 2 is a bottom perspective view thereof

FIG. 3 is a front view thereof

FIG. 4 is a back view thereof

FIG. 5 is a left-side view thereof

FIG. 6 is a right-side view thereof

FIG. 7 is a top view thereof

FIG. 8 is a bottom view thereof

FIG. 9 is a front view thereof, with an invention component in a second position; and,

FIG. 10 is a front view thereof, with an invention component in a third position.

The dash-dash-dash broken lines depict portions of the article that form no part of the claimed design.

The dot-dash-dot lines indicate the boundary of the claim and form no part of the claimed design.

Shading lines within the figures are for the purpose of illustrating the walking aid attachment's shape and are not features of the design.
